REGISTERING AND ASSEMBLING UNIT FOR
FILMS AND MOUNTS THEREFOR

Yervant H. Kurkjian, Clifton, N. J.

Application January 27, 1950, Serial No. 140,862

2 Claims. (Cl. 154—1.6)

1

This invention relates to a registering and assembling unit for films and mounts therefor, and has for one of its objects the production of a simple and efficient assembly unit, wherein the mount anchoring pins thereof are yieldably mounted, so as to prevent the penetration of the upper leaf of the mount when the sections of the unit are closed for the purpose of sealing the mount.

A further object of this invention is the production of a registering and assembling unit which will correctly and accurately hold the mount or mask in a proper position to receive the film picture sections, the unit having anchoring pins which penetrate the mask or mount, and which also extend through the sprocket apertures of the film picture sections to anchor the film picture sections in proper relation with respect to the picture framing apertures of the mount or mask.

Other objects and advantages of the present invention will appear throughout the following specification and claims.

In the drawing:

Figure 1 is a perspective view of the registering and assembling unit in an open position.

Figure 2 is an enlarged fragmentary transverse sectional view of the unit in a closed or mount sealing position, certain parts being shown in elevation.

Figure 3 is a perspective view of the mount or mask in an open position.

Figure 4 is a perspective view of the mask or mount in a closed or sealed position.

By referring to the drawing in detail, it will be seen that 10 designates the primary section of the unit, to which is hingedly connected a cover section 11 by means of a marginal hinge 12. The primary section 10 preferably comprises an upper plate 13 and a lower plate 14, which are secured together in any suitable manner.

The lower plate 14 is provided with suitable sockets, such as the sockets 15 shown in Figure 2. Registering or anchoring pins 16 extend vertically through the upper plate 13, in the manner shown in Figure 1. These pins are preferably four in number, but they may be of any desired number to hold and to properly register the film picture section or sections with the framing apertures of the mask or mount. Each pin 16 is provided with a substantially flat outer end, as shown in Figures 1 and 2, and an enlarged base 17, as shown in detail in Figure 2, which base is adapted to abut the under face of the plate 13, and thereby limit the protrusion of the pin to a selected distance beyond the upper plate 13.

2

This enlarged base 17 of each pin 16 is slidably mounted in a suitable socket, such as the socket 15 shown in Figure 2. An extension or expansion coil spring 18 normally and yieldably holds the pin 16 in an extended position. Since the pins 16 are all similarly mounted, it is thought unnecessary to illustrate the mountings of all of the pins, the structure in each instance being that as illustrated in detail in Figure 2.

10 A mask or mount 19, preferably having a plurality of film framing apertures 20 and 21 formed therein is adapted to be placed upon the upper face of the plate 13. The mask or mount 19 is preferably formed from light card board or heavy

15 paper and is preferably formed from a blank sheet, which is folded at 22, to define a pair of leaves 23 and 24. The apertures 20 and 21 of the respective leaves are adapted to register when the leaves are in a closed or sealed position, such as is shown in Figure 4. The leaf 24 shown in

20 Figure 3 is provided with pairs of aligned perforations 25 and 26, preferably located centrally of and adjacent opposite edges of the framing apertures 20 and 21 of the leaf 24.

25 The mask 19 is placed upon the section 10 of the unit as shown in dotted lines, in Figure 1, so that the pins 16 extend through the perforations such as the perforations 25. This will anchor the mask or mount in position. A film picture section, such as the section 27 is placed

30 over each framing aperture of one leaf and the sprocket apertures of the film picture section are anchored over the pins 16 so that the pins 16 extend through the sprocket apertures of the film picture section. The film picture section or sections will in this manner be firmly anchored in proper registration with the framing apertures. The leaf 23 is preferably coated with adhesive as at 23a and after the adhesive has been

35 moistened the leaf 23 is folded flat upon the leaf 24 in superimposed relation. The cover 11 is then closed over the mask or mount 19 and the primary section 14 of the unit, and pressure is applied to the cover section 11. The cover section 11 is held in a closed position a sufficient

40 length of time to seal the leaves 23 and 24 together and to lock the film picture sections firmly therebetween against accidental dislocation. Since the pins 16 are yieldably supported they will extend through the perforations 25 and 26

45 of the leaf 24 and through the sprocket apertures of the conventional picture film section to anchor the leaf 24 and picture film section or sections in position. As the leaf 23 is closed over the leaf 24 50 and the cover section is pressed to a closed sealing

position, the pins 16 will not penetrate the leaf 23 but will be depressed, thereby preventing the pin receiving perforations from showing through or being visible when viewing the pictures carried by the mask or mount.

In those instances where the pin receiving perforations are formed in both of the leaves of the mask, the unit may be used for registering and assembling the film picture sections and mask or mount without departing from the spirit 10 of the invention, in which event the pins will extend through the perforations formed in both leaves while sealing. The present device however is especially constructed for use in sealing masks and mounts which are provided with pin receiving perforations in only one leaf and to prevent the perforation of the companion leaf while sealing the mask or mount.

It should be understood that certain detail changes in mechanical structure may be provided 20 within the scope of the present invention, so long as these changes fall within the scope of the appended claims.

It should be further noted that any number of pins may be used to fit in the socket apertures of a film picture section without departing from the spirit of the invention. For instance where I have shown one pin to receive a sprocket aperture at the top of a film picture section and one to receive a sprocket aperture at the bottom, two 25 or more pins may be used in each instance if desired.

Having described the invention, what is claimed as new is:

1. A registering and assembly unit for films and mounts therefor comprising a pair of hinged sections, one section being adapted to be closed upon the other section to seal a picture mount placed therebetween, a pair of individual spring 35 pressed anchoring pins carried by one section for extending through perforations of one leaf of

a mount and for extending through the sprocket apertures of a film picture section mounted thereon, and said spring pressed anchoring pins being adapted to yield inwardly independently of each other as a companion leaf of a mount is placed over the first mentioned leaf for sealing to prevent perforation of the companion leaf.

2. A registering and assembly unit for films and mounts therefor comprising a pair of hinged sections, one section being adapted to be closed upon the other to seal a picture mount placed therebetween, a pair of individual spring 15 pressed anchoring pins carried by one section and adapted to extend through perforations formed in one leaf of a mount and also adapted to extend through the sprocket apertures of a film picture section to properly register the film picture section with the framing aperture of a mask, each pin having a substantially flat outer end, the pins being aligned outwardly away from the hinge connection of the sections and adapted to be progressively depressed as one of said sections is swung from an open to a closed position upon the other section and to avoid accidental displacement of the film while closing the sections, and means individually limiting the extension of the pins from the section of the unit carrying the pins to prevent perforation of the companion leaf of the mount as it is folded over the first mentioned leaf while sealing.
